ACCORDION GRILL

Mario Pancotti, 4 Chalford Road, Scarsdale, N.Y.

Filed Feb. 5, 1963, Ser. No. 73,455.

Term of patent 7 years

(Cl. D56—1)

FIG. 4

FIG. 1 is a top plan view of an accordion grill, showing my new design;

FIG. 2 is a front elevational view;

FIG. 3 is a side elevational view thereof; and

FIG. 4 is a perspective view thereof.

The dash dot lines on the accordion frill indicate that the ribbing shown is continuous across the inset panel while the broken line showing of an accordion in FIG. 4 is for illustrative purposes only.

I claim:

The ornamental design for an accordion grill, substantially as shown and described.
